UNITED STATES PATENT OFFICE.

WILLIAM A. DARRAH, OF CHICAGO, ILLINOIS.

OVEN.

Application filed March 19, 1920. Serial No. 367,293.

To all whom it may concern:

Be it known that I, WILLIAM A. DARRAH, a citizen of the United States, residing at Chicago, in the county of Cook and State of Illinois, have invented a new and useful Improvement in Ovens, of which the following is a specification.

This invention relates to apparatus for baking various materials and is particularly applicable for the baking of japan, the drying of paint, enamels, and similar purposes including the seasoning of wood or the burning of oil from metal or other surfaces.

Other applications of this apparatus will be apparent from the description which follows:

It is well known that the baking of japan and allied materials, as well as the drying of wood and similar operations, requires a controllable uniform temperature together with a continual flow of air or other fluid for removing the vapors given out from materials being dried.

It is further advisable in the drying of paints, japans, and similar substances, to supply a large portion of the heat in the form of radiant energy, in order to prevent the so-called "case hardening" or surface drying.

It is obvious in the drying of japans, paints, etc., that if the surface is allowed to harden before the volatile solvents are removed, that the resultant finish will be unsatisfactory due to the small pores formed in the hardened surface by the forced passage of the solvent through said surface.

It has been found that when a considerable portion of the heat is applied to the surface in a radiant form, the metal surface becomes warmer than the surrounding air within the oven, and as a result, the solvents are driven off uniformly throughout the thickness of the japan or paint before the surface has hardened.

One of the objects of this invention, therefore, is to provide an oven which will be heated by fuel but still supply a large portion of the heat in the radiant form.

Referring to the drawings, Figure 1 is an elevation showing in vertical longitudinal section, one form of oven illustrating this invention, Figure 2 shows a vertical longitudinal section through the heater, and Figure 3 shows a vertical cross section of the heater. Section line BB shows the point at which the sections given in Figure 4 was taken,

while section lines AA of Figure 2 shows the point at which the section shown in Figure 3 was taken. Figure 4 shows a vertical section, taken transversely, thru a typical oven of this kind. Figure 5 is a plan view partly in section, of a portion of the furnace which constitutes my invention. Figure 6 is a plan view partly in section, of the heating ducts within the furnace. Figure 7 is a vertical section through said heating duct. Figures 6 and 7 show the heating ducts without showing the walls of the furnace and other mechanism, in order to clearly indicate the direction of air flow and the arrangement and contour of the heating ducts. Figure 7 is a section taken on line XX of Figure 6. Figure 8 shows partly in section the means for allowing heat to escape from the heating ducts into the furnace, together with one form of operating mechanism. The reference numbers in Figures 5, 6, 7 and 8 refer to similar parts to the reference numbers in the other drawings.

Referring to the drawings, (1) indicates a blower or device for moving a fluid. (2) indicates a fire box or combustion chamber above which are mounted fluid heaters (3), through which the fluid or air from blower (1) is passed.

Burners (4) are supplied with fuel and air, and serve to supply the heat to the fire box (2).

Pipes (5) conduct air from air heaters (3) to burners (4). Ducts (6) conduct the heated air or fluid from heaters (3) to a series of flues (7) which are indicated as disposed longitudinally along the sides of the oven.

Valves (8) located along the length of flues (7) serve to release a portion of the air or fluid, passing through flues (7) allowing it to escape into the oven. Rod (9) affords a convenient means of controlling valves (8) from the exterior of the oven.

The flues (7) are of varying dimensions, having a smaller surface at one end than at the other in order to radiate different amounts of heat in different portions of the oven.

At the extreme ends of flues (7) ducts (10) are provided connecting with return flues (11) which serve to bring back the air or fluid to manifold (12) from which the returned air or fluid is directed to the blower (1).

An inlet (13) is provided in manifold

(12) at such a point that additional cold air may be added to the returning air, thus compensating for the amount of air which enters the oven through valves (8).

5 Vents (14) are provided near the central portion of the oven, connecting with duct (15) which leads the exhaust gases from the oven to stack (16).

The oven (17) consists of an elongated 10 chamber and in the cases shown, is provided with inclined vestibules (18) and 20 at the entering and exit ends respectively.

The exact structure of the oven is not essential to the spirit of this invention, the 15 main essentials being a fairly rigid structure of materials unaffected by heat.

It is desirable to provide heat insulating materials for covering the walls and all surfaces of the oven.

20 The ovens should also be constructed so that they will be air tight throughout their length.

In operation, the material to be baked or dried will enter at door (19), pass upward through vestibule (18) and along the 25 length of oven (17) leaving by vestibule (20) and door (21).

Air from the blower will pass through the air heaters which are maintained from 800 30 to 1400 degrees F. The heaters will raise the temperature of the air to about 600 to 700 degrees F., depending on velocity and the design of the oven.

The heated air will pass through ducts 35 (6) into heating flues (7). The passage of the heated air through these flues will raise their temperature to from 500 to 600 degrees F., thus making them act as large radiating surfaces which will thus radiate heat 40 to the materials to be dried.

It will be noted that at the entering vestibule (18) where the materials are relatively cool, the radiating surface of the flues is far greater than at other portions of the 45 oven. In general it is desirable to have the radiating surface of the flues taper gradually to a minimum value at the exit end of the oven. The object of the tapering arrangement here described is to provide a 50 radiating surface which is proportional to the heat absorbed by the material passing through the oven. Substantially the same object may be accomplished by causing the radiating surface of the flues to taper from the central portion of the oven, where they 55 have a minimum value, to the entering end of the oven where they have a maximum value, while in the portion of the oven from the central part to the leaving end the 60 amount of radiating gases may be so reduced that the heat supplied will merely compensate for radiation and other losses. In this case, the taper of the flue surface is of relatively minor importance.

65 As the materials to be dried enter at ves-

tibule (18) they are first heated by radiation from flues (7) and then having attained a relatively elevated temperature, they are carried along by a continuous conveyor (22) until they reach the stream of circulating air 70 which enters the oven from valves (8). The air which enters at this point serves to carry off the fumes of the evaporating solvent which, if not removed, are likely to accumulate to a dangerous degree and cause explosions. 75

The temperature of the oven may be controlled by means of a thermo-couple (23) inserted in a manifold (24) which connects the air heater with ducts (6). The thermo-couple (23) is connected with any standard pyrometer (25) which actuates a relay (26) by means of a battery (27) whenever the temperature rises above the desired value. The relay (26) operates an electrically controlled oil valve (27a) in fuel line (28) which supplies fuel to burner (4). 80

One preferred form of this invention consists in having a series of burners supplying heat to combustion chamber (2) and causing the thermo-couple (23) to control the fuel supply of only one burner (4) of the series. 90

By this system the fuel supply to burner (4) is either entirely open or entirely closed, depending upon the temperature of the air in manifold (24). 95

It will be noted that valves (8) are so located as to permit the air from flues (7) to enter the oven after a portion of the heat from the said air has been given up to the flues and radiated to the material in the oven. 100

It will be further noted that the ventilating air enters at the portion of the oven at which the material to be dried, is cooled and travels with the material, thus becoming saturated with vapors of the solvent of the japan and reducing "case hardening" to a minimum. 105

By passing the exhaust gases from combustion chamber (2), through stack (16), a permanent draft is established which insures that the circulating air which leaves the oven by conductor (14), will be positively exhausted. It is of decided advantage to utilize a positive exhaust of this kind, although I do not wish to restrict this invention to a stack draft, as obviously, a blower or other equivalent may be employed. 110

One of the advantages resulting from adding the cold "make-up" air to manifold (12) at point (13) consists in reducing the temperature of the air handled by the blower (1). 115

It will be evident that the air used as a circulating medium after having absorbed the vapors of the japanned solvent, cannot be re-circulated to advantage without the danger of accumulating considerable amount of solvent vapor. On the other hand, the 120 125 130

air which has been used for heating and radiating flues (7) may be returned to the heaters and re-circulated, thus saving a very considerable amount of heat. This feature 5 permits a relatively high economy of the oven which forms the basis of this invention.

Having now fully described this invention what I claim as new and wish to secure by Letters Patent in the United States, is as 10 follows:

1. A heating oven consisting of a chamber, a heating device, a means of moving air through said heating device, closed radiating containers disposed in said oven and heated 15 by the passage of said hot air therethrough, escape openings connecting to said closed radiating containers, said radiating containers exposing a graduated radiating surface to the interior of said oven.

2. A heating oven consisting of a firebox, a source of air under pressure, means for heating said air by said fire box, a radiating container disposed in said oven and heated by the passage of said air, and means for 20 allowing a portion of said air to escape into the oven.

3. In a heating oven a metal duct presenting a large surface for radiation, said surface arranged to be greater at the portion of the oven at which the material to be heated enters, and less at the opposite portion.

4. In a heating oven, a radiating duct therein, said duct arranged to conduct hot 35 gases through said oven and to radiate a portion of the heat of said gases to the contents of said oven, the surface of said duct being graduated to be greater at the entering portion of said oven and less at the central portion.

5. A heating oven consisting of a fire box, a source of air under pressure, means for heating said air by said fire box, a radiating container in said oven, and heated by passage 45 of said air, means for allowing a portion of said air to escape into the oven, and means for positively exhausting the said escaping air.

6. In a heating oven a metal duct of graduated radiating surface arranged to heat

said oven by radiation, and means for permitting the escape of a controlled amount of the gases passing through said duct.

7. In a continuous oven, a system of ducts for conducting hot gases therethrough, the 55 radiating surface of said ducts being so proportioned that the heat given up by said radiating surface to the materials being heated in the oven, will be a maximum at the entering end and become successively less as the duct passes from the entering end.

8. A heating oven consisting of a chamber, closed radiating containers disposed in said oven, a heating device, a means of moving air through said heating device without 65 contact with the products of combustion, connection with said heating device and said closed radiating containers, escape openings connected to said closed radiating containers, said radiating containers exposing a 70 graduated radiating surface to the interior of said oven.

9. In a heating device, a multiple of burners supplying heat, a thermostat operated by the heat so supplied, a relay device controlled by said thermostat, a means for causing said relay device to open or close a part only of said multiple of burners in order to maintain constant temperature conditions.

10. A heating oven consisting of a chamber, a heating device, a means of moving air through said heating device, closed radiating containers disposed in said oven and heated by the passage of said hot air therethrough, escape openings connected to said 85 closed radiating containers, and return connections from said closed radiating containers to said heating device and said means of moving air.

11. A heating oven consisting of a chamber, a heating device, a means of moving air through said heating device, closed radiating containers disposed in said oven and heated by the passage of said hot air therethrough, escape openings connected to said 95 closed radiating containers, and a connection between said closed radiating containers and said means of moving air.

WILLIAM A. DARRAH.
